(57) **CLAIM**

The ornamental design for a portion of an examination chair, as shown and described.

DESCRIPTION

FIG. 1 is a front perspective view of the portion of an examination chair according to the invention.

FIG. 2 is a rear perspective view of the portion of an examination chair according to the invention.

FIG. 3 is a front elevational view of the portion of an examination chair according to the invention.

FIG. 4 is a left side view of the portion of an examination chair according to the invention, the right side view being a mirror image of the left side view.

FIG. 5 is a rear view of the portion of an examination chair according to the invention.

FIG. 6 is a top elevational view of the portion of an examination chair according to the invention; and,

FIG. 7 is a bottom elevational view of the portion of an examination chair according to the invention.

Any elements shown in dash-dot lines form no part of the claimed invention in this application, and are instead included to show environmental structure associated with the claimed invention.

1 Claim, 3 Drawing Sheets
